UNITED STATES PATENT OFFICE

CHARLES CALVIN READ, OF MANDARIN, FLORIDA.

WATERING-POT.

SPECIFICATION forming part of Letters Patent No. 443,717, dated December 30, 1890.

Application filed October 28, 1890. Serial No. 369,615. (No model.)

To all whom it may concern:

Be it known that I, CHARLES CALVIN READ, a citizen of the United States, residing at Mandarin, in the county of Duval and State 5 of Florida, have invented a new and useful Watering-Pot, of which the following is a specification.

This invention has relation to improvements in watering-pots for use in sprinkling 10 gardens, washing the outside of buildings, distributing poison on plants, &c.

The objects in view are to provide a reservoir or pail adapted to be carried by hand, and to combine with the same a simple and 15 efficient pump for throwing the water from the pail, and to accomplish the same without the exercise of undue power and partially by the weight of the water within the bucket or pail.

20 With the above objects in view the invention consists in certain features of construction hereinafter specified, and particularly pointed out in the claims.

Referring to the drawings, Figure 1 is a side 25 elevation of a pump constructed in accordance with my invention. Fig. 2 is a transverse vertical section through the rack-bar and pinion. Fig. 3 is a similar view through the pump-cylinder. Fig. 4 is a bottom plan.

30 Like numerals of reference indicate like parts in all the figures of the drawings.

1 designates the bucket or pail, of suitable dimensions, and provided with the lifting bail or handle 2 and the removable cover 3, which 35 latter is supplied with a flanged opening 4, covered by a pivoted balanced door 5. At intervals the sides of the bucket or pail are provided with vertical series of loops or keepers 6, in which are loosely mounted a series 40 of supports 7. The supports 7 are bent under the bottom of the bucket and are secured to a standard or post 8, terminating at its lower end in a suitable base 9, in this instance a series of radiating feet.

45 10 designates the pump-cylinder, which communicates through the bottom of the bucket by means of short pipes 11 and 12, having downwardly-opening valves 13 at their upper ends. Opposite the pipes 11 and 12 pipes 14 50 communicate with the cylinder, and the same merge into a single discharge-pipe 15, bent

up to the side of the bucket and coupled with a flexible hose 16. Outwardly-opening valves 17 are mounted in the inner ends of the branch pipes 14.

55

16' designates a depending bail loosely hinged, as at 18, to the bottom of the bucket. The lower end of the bail terminates in bearings 19, in which is mounted a transverse shaft 20, carrying a small gear 21, and outside of one of its bearings terminating in a crank-arm 22. Loosely connected to the crank-arm is the outer end of a connecting-rod 23, the inner end being loosely secured to a U-shaped piston 24, one terminal of which 60 is mounted for reciprocation in a depending bracket 25, and the opposite terminal of which reciprocates in the cylinder 10, carries a suitably-packed piston-head 27, and is suitably packed itself at the end of the piston. 70

Two of the adjacent legs or supports 7 are connected by a cross-bar 28, and to the cross-bar and one of the supports is secured a rack-bar 29, adapted to engage and operate the small gear described, which latter is maintained in engagement with the rack-bar through the medium of a small coiled spring 30. 75

31 designates the thumb-lever mounted in a keeper 32, having its upper end bent and 80 occurring adjacent to the handle of the bucket, and its lower end bent under the bottom and loosely connected with the crank-shaft of the small pinion.

The operation of the invention will be readily understood from the foregoing description, when taken in connection with the accompanying drawings; but in order to render the same clear and explicit the following brief description is given: The pail is filled with 85 water and carried to the point of use, where it is stood upon the ground. By lifting upon the handle of the bucket said bucket is drawn away from the base or support, the rods or supports 7 readily sliding in the keepers. The 90 rack-bar remaining stationary and the gear moving with the bucket, the latter, together with the crank-shaft, is rapidly rotated, and the piston is rapidly reciprocated within the cylinder. The pump is after the character of 95 the well-known double-acting pump and alternately induces water through the pipes 11 100

and 12 into the cylinder and forces the same alternately through the branches 11^a of the discharge, and so it is apparent that a steady stream or discharge is maintained, the force 5 of which may be regulated by the violence and power employed in moving the bucket up and down. When the bucket has reached its upstroke, it is then depressed, and the operation is similar to that just described. It 10 will be observed that the weight of the water in the bucket will serve ordinarily as the means for the return-stroke; but by adding manual pressure to the weight of the water the stream can be forced farther.

15 From the above construction it will be seen that I provide an extremely cheap, serviceable, and efficient combined pump and bucket, the pump being located under the bucket, and therefore out of the way and adding but 20 little weight to the device. By the balance-door, located in the top, the water is prevented from spilling, as from an ordinary bucket connected to a pump.

By pressing upon the lever 31 the swinging bail may be drawn inwardly and the cog or pinion 21 withdrawn from engagement with the rack-bar, so that the pail may be lifted without raising the support and the pump operated with the down or up stroke, or 30 merely with the downstroke alone.

Having described my invention, what I claim is—

1. The combination, with a bucket, of a base, a pump located under the bucket and communicating with the bucket and provided with a discharge, and connections between the pump-piston and bucket, whereby movement of the bucket upon the base will cause a reciprocation of the piston, substantially as 35 specified.

2. The combination, with a bucket provided with a series of vertically-opposite keepers, of rods mounted in the keepers, extending under the bucket, and secured to a support, a 40 pump-cylinder communicating near its ends

with the bucket and provided with a discharge extending up through the side of the bucket, a crank-shaft supported under the bucket, a pinion mounted thereon, a rack-bar secured to one of the rods and engaging with 50 the pinion, and a connecting-rod leading from the crank of the shaft to the piston-rod of the pump, substantially as specified.

3. The combination, with the bucket having the handle and the movable cover and provided in its sides with the series of opposite keepers, of rods loosely mounted in the keepers and connected to a suitable base, a double-acting pump located under the bucket and having a U-shaped piston-rod, the outer 60 terminal of which is supported in position in a bracket under the pump, a hinged bail located under the bucket, a crank-shaft journaled therein, a pitman connecting the crank-shaft with the piston-rods, a gear mounted 65 on the shaft, a rack-bar secured to one of the rods and engaging and driving the gear, and a spring for pressing the gear into engagement with the rack-bar, substantially as specified.

4. The combination, with the bucket, the pivoted depending bail, the cranked shaft journaled therein, the pinion mounted upon the shaft, the pump-cylinder, and the piston mounted therein and connected to the said 70 crank-shaft, of the standard, the rods projecting therefrom and passed through keepers upon the bucket, the rack-bar rigidly connected to the base, and the thumb-lever located and supported at one side of the bucket, 75 bent under the same, and connected at its lower end to the depending pivoted bail, substantially as specified.

In testimony that I claim the foregoing as my own I have hereto affixed my signature in 80 presence of two witnesses.

CHARLES CALVIN READ.
